DESIGN FOR AN ILLUSION DEVICE.

55,960.

Specification for Design.

Patented Aug. 3, 1920.

Application filed May 8, 1919. Serial No. 295,790. Term of patent 3½ years.

To all whom it may concern:

Be it known that I, VINCENT N. SIMON, a citizen of the United States, residing at Chicago, in the county of Cook and State of Illinois, have invented a new, original, and ornamental Design for an Illusion Device, of which the following is a specification, reference being had to the accompanying drawings, forming part thereof.

In the drawings—

Fig. 2 is a perspective view showing the manner of using the device in association with the human hand, the curved stem of the device being hooked between the knuckles of the index and middle fingers of the left hand, the fingers being bent inwardly on the palm and a cloth or other covering draped over the clasped hand.

I claim:

The ornamental design for an illusion device, as shown.

VINCENT N. SIMON.
